(57) **CLAIM**

The ornamental design for a power storage system, as shown and described.

DESCRIPTION

FIG. 1 shows a top front isometric view of a module of a power storage system in accordance with the present design. FIG. 2 shows a bottom rear isometric view of the module in FIG. 1.

FIG. 3 shows a front view of the module in FIG. 1.

FIG. 4 shows a rear view of the module in FIG. 1.

FIG. 5 shows a left side view of the module in FIG. 1.

FIG. 6 shows a right side view of the module in FIG. 1.

FIG. 7 shows a top view of the module in FIG. 1; and,

FIG. 8 shows a bottom view of the module in FIG. 1.

The even dash broken lines represent environment that forms no part of the claimed design. The dash-dot broken lines represent the boundary of the claim and form no part of the claimed design.
